METHOD OF PRODUCING COLOR SEPARATION IMAGES

Béla Gáspár, Hollywood, Calif., assignor to
Chromogen, Incorporated, a corporation of
Nevada

Application January 24, 1941, Serial No. 375,849

12 Claims. (Cl. 95—2)

My invention pertains to the use of multilayer materials for the making of photographs and to the production of color separations from such photographs. Heretofore, it has been the common practice to develop, and tone or otherwise transform into dye images all of the components or part-images in such a multilayer material, and then use them for the making of copies or color separations. In other words, all of these prior processes involve development of all of the part-images prior to the copying step.

It is an object of my invention to provide a new and improved method for the preparation of color separations wherein preferably only one of the superposed and integrally united layers of a multilayer material, each containing a latent image of a color separation, is separately developed and printed without affecting the latent images in the other layers.

Another and still further object of my invention is to provide such a process in which the integrally attached layer containing a latent image is rendered optically homogeneous so that the developed image may be printed therethrough without interference.

To these and other ends the invention resides in certain improvements in processing methods and in combinations of elements all as will be more fully described hereinafter, the novel features being pointed out in the claims appended hereto.

In the accompanying drawing, Fig. 1 is a sectional view of a bipack film having three light-sensitive layers and a filter layer, one of the layers being a reversal emulsion. Fig. 2 shows a sectional view of a multilayer material having three light-sensitive layers and a filter layer on a single support, two of the emulsion layers being reversal emulsions. Figure 3 likewise shows a multilayer material having three light-sensitive layers and two filter layers, all of the light-sensitive layers being reversal emulsions.

Example one

In Figure 1 of the accompanying drawing, I have shown a multilayer photographic material in the form of a bipack which may be used as a taking material and later processed in accordance with my invention. The material is adapted for exposure through the support 1. This bipack includes a transparent blue-sensitive emulsion layer A on the front support 1. Over this blue-sensitive emulsion layer is coated a yellow filter layer A' containing one gram of calcium salt of the dye xylenwalgelb G (Schultz Farbstoffeta-

10 bellen, Leipzig, 1931, vol. 2, pg. 232) per square meter in gelatin. The back element of the bipack includes a support 2 which carries a red-sensitive silver bromide emulsion layer C sensitized with pinacyanol. Layer C is a reversible silver bromide emulsion, and is preferably an emulsion of the reversal type which has similar properties as to gradation and contrast as those found in ordinary reversible cinema films. On top of this layer C is coated a green-sensitive emulsion layer B which has been sensitized with thiopseudocyanine.

15 The bipack material shown in Fig. 1 is exposed in a camera, separated, and the front element including the layer A is developed normally, whereupon the image may be printed onto a positive film to form a blue separation master positive. The back element of the bipack is developed in a rapid developer, such for example as the following:

Water	cc	750
Methyl alcohol	cc	48
Metol	cc	14
Hydroquinone	cc	14
25 Sodium sulphite anhyd	grams	52.5
Sodium hydroxide	do	8.8
Potassium bromide	do	8.8
Water to	cc	1000

20 This rapid development is caused to take place in such a way as to develop only the surface layer B with the aforementioned developer. The time of development has been found to take approximately one minute. However, the exact time of development for any particular material should be established by a preliminary test. When the surface layer B has been developed, development is stopped with a 1% solution of acetic acid and the film is washed and dried. The film is then printed with infra-red light having a wave length of over 700 $\mu\mu$ onto a positive film which has been sensitized to infra-red with cryptocyanine or benzthiotoricarbocyanine. One thus obtains a green separation master positive from the developed image in layer B without disturbing the latent image in layer C.

25 After the surface layer B has been printed, the underlying layer C is developed and the developed silver is bleached in both layers B and C. This may be done by transforming the silver bromide by treatment with a 10% solution of cupric bromide for about 10 minutes. As a result of this treatment layer B is rendered optically homogeneous, i. e., it contains the original

unexposed silver bromide and the transformed silver image in the form of comparatively insensitive silver bromide. The back element is then exposed with intense red light to expose the remaining silver bromide in layer C which is still red sensitive. Layer C may now be developed and a reversed image of the red separation image will be produced therein. This image may be printed with infra-red light or even with red light on a red-sensitive film, since layer C is no longer red-sensitive and layer B is only sensitive to green with a possible inherent sensitivity to blue. Due to the fact that layer B is optically homogeneous it presents a minimum of interference to the passage of the printing light.

It will be understood of course that the print obtained by printing layer C will be a negative, whereas the prints obtained from layers A and B will be positives. This fact must be taken into consideration during the subsequent utilization of the prints.

A simple modification of the material shown in Fig. 1 is to interpose a filter layer between the layers B and C and to color this filter layer with a yellow dye which will absorb blue and ultra-violet. It is then possible to expose layer C through the support to a strong blue or ultra-violet light in order to accomplish the reversal, and the filter layer prevents the exposure from affecting layer B.

Example two

In Fig. 2 I have shown a multilayer material in which three light sensitive silver halide layers are coated on a single support 2. On this support is coated a red sensitive silver halide emulsion C of the reversal type, and superposed with respect to this is a green sensitive emulsion B also of the reversal type. On top of this emulsion B is coated a filter layer A' containing a yellow dyestuff, as in Fig. 1, followed by an ordinary blue sensitive emulsion A.

After this material has been exposed in a camera in the ordinary manner, the top layer A is developed in a rapid developer as described in Example one, and the developer is controlled in such a way as to interrupt the development after the layer A has been completely developed. The image in layer A is then printed with infra-red light onto an infra-red sensitive film as also described in Example one. Following the printing of the image in layer A, the remaining layers B and C are developed in an ordinary developer and the film is treated with a solution of $\frac{1}{2}\%$ acetic acid which acts as a stop bath, and washed. It is then treated with a bath containing 2-5% of potassium ferricyanide and 0.5-2% potassium iodide to transform the developed silver images in all of the layers into silver iodide. The developed silver images can also be transformed into a comparatively insensitive silver bromide by treating them with a 10% solution of cupric bromide as described in Example one. Either treatment renders all of the layers optically homogeneous. The film is now washed and dried and exposed with intense red light and again developed to form a reversal image in layer C. This image may now be printed with infra-red light or with red light, since none of the layers is sensitive to light outside the blue and green spectral ranges.

Here again the fact that layers A and B have been rendered optically homogeneous at the time the reversed image in layer C is printed, facilitates the passage of the printing light with

7 a minimum of interference. The layers contain the original silver bromide which has not been fixed out, and also the original images recorded therein. However, the original images are now 10 in the form of silver iodide or silver bromide which has substantially the same optical properties as the original silver bromide. This condition is important, since if the developed silver images in all of the layers had been dissolved prior to reexposure and printing of layer C, then at the time of printing the image in layer C it would have been falsified by the minor but material opacity of the residual silver salt images in layers A and B.

15 After the reversed image in layer C has been printed onto a separate material sensitive to the light utilized for printing, the film is again treated with either of the above mentioned bleaching baths to transform the reversed silver image in layer C back into either silver iodide or comparatively insensitive silver bromide, thus 20 making layer C optically homogeneous again. The film is then again exposed to intense green light to reverse the image in layer B. This reversed image in layer B can be printed with infra-red light, red or even green light, or the 25 silver salt can be fixed out of the whole film and the image in layer B can then be printed with white light.

30 After the bleaching steps in the foregoing procedure, the film can be treated in a 5% solution of sodium sulphite to which some sodium hydroxide or some ammonia may be added, in order to increase its sensitivity. Alternatively, 35 one may use a bath containing 0.5-10 cc. of concentrated ammonia per liter of water.

In this example, as in Example one, due allowance must be made in utilizing the prints made from the images in layers A, B and C, 40 for the fact that the images obtained from layers B and C are negatives while the image obtained from layer A is a positive.

Example three

45 The material shown in Fig. 3 has three light sensitive silver halide layers superposed on a support. The layer C is a red sensitive layer, the layer B is a green sensitive layer, and the layer A is an ordinary blue sensitive layer. Interposed between layers A and B is a yellow filter layer A', and if desired a red filter layer B' is interposed between layers B and C. All of 50 these light sensitive emulsions are reversal emulsions. They may be sensitized as disclosed in Example one, and the filter layer A' may be dyed with the yellow dye suggested in Example one while the filter layer B' may be dyed with any suitable red dyestuff such as 1 gram of Pararad per square meter as described in my 55 U. S. Patent 2,172,307.

60 After exposure in a camera in the ordinary way, the film is developed with an ordinary developer to form a silver image in each of the three layers. Following development, the film 65 is treated with a $\frac{1}{2}\%$ solution of acetic acid which acts as a stop bath, and washed but not fixed. The developed silver images in all three layers are then transformed into silver salt images by treatment in either of the following 70 solutions:

(1) A solution of 2-5% of potassium ferricyanide and 0.5-2% potassium iodide.

(2) A 10% solution of cupric bromide.

Treatment in solution (1) results in the transformation of the developed silver images into

silver iodide after a treatment lasting from 5-15 minutes. Treatment with solution (2) results in the transformation of the developed silver images into a comparatively insensitive silver bromide after a treatment of about ten minutes. Treatment of the film with either of these solutions results in the production of optically homogeneous layers as brought out in Example two.

Following the foregoing treatment, the film is washed and dried. It is then exposed with an intense red light which affects the undeveloped silver bromide in the red sensitive layer C. Following this reexposure the film is developed to form a reversal of the red separation image in layer C and the film is washed, dried and printed with infra red or red light onto an infra red or red sensitive film to produce a negative of the red separation image. Following this printing step the film is again treated with either solution (1) or (2), whereby the positive image in layer C is bleached and layer C is rendered optically homogeneous. After being again washed and dried, the film is exposed to a strong green light which affects the undeveloped silver bromide in layer B. After development a reversed image is formed in layer B and this image can be printed with infra red, red, or even green light onto a suitably sensitized film. The print thus obtained represents a negative green separation image. The film is now treated for a third time with either solution (1) or (2) to bleach the reversed image in layer B and to render this layer optically homogeneous. The film may now be exposed to blue light and developed to produce a reversed image in layer A. This image can then be printed as above described to produce a negative of the blue separation image. It is also possible to fix the film following development of the last reversed image, in which case the reversed image in layer A could be printed with ordinary white light.

It will be understood, of course, that the order of reexposure and printing can be varied. For example, the image in layer B might be reversed and printed first instead of the image in layer C. If layer B is reversed and printed first, it might be printed with red light onto a red sensitive layer even though layer C still contains red sensitive silver bromide. The printing of layer B with red light would, of course, cause a certain proportion of the red sensitive silver bromide in layer C to be exposed. However, this does not interfere with the succeeding treatment of layer C since following the printing of the image in layer B, layer C is completely exposed to red light. Therefore, the incidental exposure of layer C during the printing of layer B is merely cumulative with regard to the complete exposure of layer C and the reversed image produced in layer C will be just the same even though layer C was incidentally exposed during the printing of layer B. In this regard it will be noted that the improved process is not limited to printing one of the developed images with light to which none of the other light sensitive layers is responsive. It will be understood, of course, that if any one of the layers is printed with light which would be absorbed by the filter dye in the intervening filter layers, it is necessary to remove this dye prior to such printing.

The advantages of the present method will be readily understood from a consideration of the foregoing examples, and it is to be particularly noted that the method excels in its simplicity and in the fact that intricate toning and dyeing proc-

esses are eliminated. Also, the overlapping of individual part images is totally eliminated, and this is a result that can normally be obtained only when separation part images are made from multicolor part images of a multilayer material by the application of cumbersome methods.

I have herein shown and particularly described certain embodiments of my invention and variations of the improved method embraced therein for the purpose of explaining its principle and application but it will be obvious to those skilled in the art that many modifications and other variations are possible. For example, I have particularly referred to what are commonly known in the art as reversal type silver halide emulsions. As is equally well known, any normal silver halide emulsion can be reversed and, accordingly, it should be definitely understood that when I refer to reversible emulsions I mean to include any emulsion which can be reversed whether or not it is specially adapted for such treatment.

What I claim and desire to secure by Letters Patent is:

1. The method of producing photographic images from a multilayer photographic material including a plurality of light sensitive silver halide emulsion layers each containing a latent image which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light sensitive silver halide in one of said emulsion layers, and developing and printing the resulting reversal image.
2. The method of producing photographic images from a multilayer photographic material including a plurality of light sensitive silver halide emulsion layers each containing a latent image and at least one of said emulsion layers being of the reversal type which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light sensitive silver halide in said reversal emulsion layer, and developing and printing the resulting reversal image.
3. The method of producing photographic images from a multilayer photographic material including a plurality of light sensitive silver halide emulsion layers each containing a latent image which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light sensitive silver halide in one of said emulsion layers, developing and printing the resulting reversal image, transforming said reversal image into a silver salt having substantially the same optical properties as the remaining silver salt in said one of said

emulsion layers and having substantially no sensitivity to the light and substantially no reactivity with regard to the developer used in the further processing, selectively exposing the remaining light sensitive silver halide in another emulsion layer, and developing and printing the resulting reversal image in said other emulsion layer.

4. The method of producing photographic images from a multilayer photographic material including three light sensitive silver halide emulsion layers each containing a latent image which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light sensitive silver halide in one of said layers, developing and printing the resulting reversal image, transforming the developed reversal image into a silver salt having substantially the same optical properties as the remaining silver salt in said one of said layers and having substantially no sensitivity to the light and substantially no reactivity with regard to the developer used in the further processing, selectively exposing the remaining light sensitive silver halide in one of the other emulsion layers, developing and printing the resulting reversal image in the last mentioned layer, transforming the developed image in said last mentioned layer into a silver salt having substantially the same optical properties as the remaining silver salt in the layer and having substantially no sensitivity to the light and substantially no reactivity with regard to the developer used in the further processing, selectively exposing the remaining light sensitive silver halide in the third emulsion, and developing and printing the resulting reversal image.

5. The method of producing photographic images from a multilayer photographic material including three light sensitive silver halide emulsion layers each containing a latent image which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light sensitive silver halide in one of said layers, developing and printing the resulting reversal image, transforming the developed reversal image into a silver salt having substantially the same optical properties as the remaining silver salt in said one of said layers and having substantially no sensitivity to the light and substantially no reactivity with regard to the developer used in the further processing, selectively exposing the remaining light sensitive silver halide in one of the other emulsion layers, developing and printing the resulting reversal image in the last mentioned layer, transforming the developed image in said last mentioned layer into a silver salt having substantially the same optical properties as the remaining silver salt in the layer and having substantially no sensitivity to the light and substantially no reactivity with regard to the developer used in the further processing, selectively expos-

ing the remaining light sensitive silver halide in the third emulsion, developing, fixing, and printing the resulting reversal image.

6. The method of producing photographic images from a multilayer photographic material including a plurality of light sensitive silver halide emulsion layers each containing a latent image which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light sensitive silver halide in one of said emulsion layers, and developing and printing the resulting reversal image with infra red light.

7. The method of producing photographic images from a multilayer photographic material including three light sensitive silver halide emulsion layers on the same side of a single support each containing a latent image which comprises, developing the latent image in the surface emulsion layer only, printing the developed image, developing the latent images in the emulsion layers next to the support, transforming the developed images in all of said layers into a silver salt having substantially the same optical properties as the unexposed silver halide in said layers and having substantially no sensitivity to the light and substantially no reactivity with regard to the developer used in the further processing, selectively exposing the remaining light sensitive silver halide in one of said emulsion layers next to the support, developing and printing the resulting reversal image, transforming the developed image in said last mentioned emulsion layer into a silver salt having substantially the same optical properties as the remaining silver salt in the layer and having substantially no sensitivity to the light and substantially no reactivity with regard to the developer used in the further processing, selectively exposing the remaining light sensitive silver halide in the third emulsion layer, and developing and printing the resulting reversal image.

8. The method of producing photographic images from a multilayer photographic material including a plurality of light-sensitive silver halide emulsion layers on the same side of a single support each containing a latent image which comprises, developing the latent image in the surface emulsion layer only, printing the developed image, developing the other latent images, transforming all developed silver in all of the layers into a silver salt having substantially the same optical properties as the unexposed silver halide in said layers and having substantially no sensitivity to the light and substantially no reactivity with regard to the developer used in further processing, successively and selectively exposing the remaining light-sensitive silver salt in the emulsion layers other than the surface emulsion layer and developing the exposed layer to form reversal images, said successively produced reversal images being printed and thereafter converted, prior to the exposure of another layer, into a silver salt having substantially the same optical properties as the remaining silver salt in the layer and having substantially no sensitivity to the light and no reactivity with regard to the developer used in further processing.

9. The method of producing photographic images from a multilayer photographic material including a plurality of light-sensitive silver halide emulsion layers on the same side of a single support each containing a latent image which comprises, developing the latent image in the surface emulsion layer only, printing the developed image with infrared light, developing the other latent images, transforming all developed silver in all of the layers into a silver salt having substantially the same optical properties as the unexposed silver halide in said layers and having substantially no sensitivity to the light and substantially no reactivity with regard to the developer used in further processing, successively and selectively exposing the remaining light-sensitive silver salt in the emulsion layers other than the surface emulsion layer and developing the exposed layer to form reversal images, said successively produced reversal images being printed and thereafter converted, prior to the exposure of another layer, into a silver salt having substantially the same optical properties as the remaining silver salt in the layer and having substantially no sensitivity to the light and no reactivity with regard to the developer used in further processing.

10. The method of producing photographic images from a multilayer photographic material including a plurality of light-sensitive silver halide emulsion layers each containing a latent image which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light-sensitive silver halide in one of said emulsion layers, developing and printing the resulting reversal image, transforming said reversal image into a silver salt having substantially the same optical properties as the remaining silver salt in said one of said emulsion layers and having substantially no sensitivity to the light and substantially no reactivity with regard to the developer used in the further processing, selectively exposing the remaining light-sensitive silver halide in another emulsion layer, and developing the resulting reversal image in said other emulsion layer.

11. The method of producing photographic images from a multilayer photographic material including a plurality of light-sensitive silver halide emulsion layers each containing a latent image which comprises, developing the latent

images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light-sensitive silver halide in one of said emulsion layers, developing and printing the resulting reversal image, transforming said reversal image into a silver salt having substantially the same optical properties as the remaining silver salt in said one of said emulsion layers and having substantially no sensitivity to the light and substantially no reactivity with regard to the developer used in the further processing, selectively exposing the remaining light-sensitive silver halide in another emulsion layer, and developing the resulting reversal image in said other emulsion layer and fixing the film.

12. The method of producing photographic images from a multilayer photographic material including three light-sensitive silver halide emulsion layers each containing a latent image which comprises, developing the latent images in said emulsion layers, transforming the developed images into a silver salt having substantially the same optical properties as the unexposed silver halide in said layers and having substantially no sensitivity to the light and substantially no reactivity with regard to the developer used in the further processing, selectively exposing the remaining light-sensitive silver halide in one of said layers, developing and printing the resulting reversal image, transforming the developed reversal image into a silver salt having substantially the same optical properties as the remaining silver salt in said one of said layers and having substantially no sensitivity to the light and substantially no reactivity with regard to the developer used in the further processing, selectively exposing the remaining light-sensitive silver halide in one of the other emulsion layers, developing and printing the resulting reversal image in the last mentioned layer, transforming the developed image in said last mentioned layer into a silver salt having substantially the same optical properties as the remaining silver salt in the layer and having substantially no sensitivity to the light and substantially no reactivity with regard to the developer used in the further processing, selectively exposing the remaining light-sensitive silver halide in the third emulsion, developing and fixing the film.

BÉLA GÁSPÁR.
